SERVING CART

Domenico Intorcio, 1524 Euclid Ave., Cleveland, Ohio

Filed Dec. 29, 1960, Ser. No. 63,391

Term of patent 14 years

(Cl. D33—14)

I claim:

The ornamental design for a serving cart, substantially as shown.
